(57) **CLAIM**

The ornamental design for a note paper as shown and described.

DESCRIPTION

FIG. 1 is a front view of a note paper showing our new design;

FIG. 2 is a rear view thereof; and,

FIG. 3 is an enlarged detail view of area 3 shown in dot dash broken lines in FIG. 1.

The dotted lines in FIGS. 1 and 3 form part of the claimed design. The evenly spaced broken lines shown in the drawings depict portions of the note paper that form no part of the claimed design. The dot dash broken lines in FIGS. 1 and 3 denote the boundaries of the enlarged detail view and form no part of the claimed design.

1 Claim, 3 Drawing Sheets
